UNITED STATES PATENT OFFICE.

JESSE W. SIMMONS, OF NEVADA, TEXAS.

DOOR-SECURER.

1,171,266.

Specification of Letters Patent.

Patented Feb. 8, 1916.

Application filed May 6, 1915. Serial No. 26,349.

To all whom it may concern:

Be it known that I, JESSE W. SIMMONS, a citizen of the United States, residing at Nevada, in the county of Collin and State of Texas, have invented certain new and useful Improvements in Door-Securers; and I do declare the following to be a full, clear, and exact description of the invention, such as will enable others skilled in the art to which it appertains to make and use the same.

This invention relates to improvements in door securers and more particularly to portable devices of this character.

15 The object of the invention is to provide a simply constructed portable door securer which is designed to be carried in the pocket or grip and to be readily attached to a door from the inside to prevent unauthorized entry and which is adjustable to provide for its application to any door without altering or marring the door and without the use of bolts of any sort and which is designed to be used instead of or in addition 20 to the usual lock provided on doors.

With this object in view, the invention consists of certain novel features of construction, and the combination and arrangement of parts as will be more fully described 30 and claimed.

In the accompanying drawings: Figure 1 represents a transverse section of a door and its frame showing this improved securer applied; Fig. 2 is a vertical section taken on the line 2—2 of Fig. 1; Fig. 3 is a transverse section taken on the line 3—3 of Fig. 1; Fig. 4 is a detail perspective view of the cross-bar constituting one member of this securer; Fig. 5 is a plan view of the nut employed in connection with the securer, and Fig. 6 is a view similar to Fig. 1 showing the device applied in a different manner.

In the embodiment illustrated, a door jamb 1 is shown provided with the usual recess 2 for the latch or bolt, not shown, of the lock carried by the door 3. The improved securer contemplated by the present invention comprises a cross bar 4 designed for spanning the joint between the jamb 1 and the door 3 and which is preferably L-shaped as shown, the short arm 5 thereof being designed for a purpose hereinafter to be described. The long arm 6 of this cross bar is provided on its opposite faces with sockets 7, two being shown on its outer face and one on its inner face, although any desired number may be employed on either face. A connector 8 for clamping this cross bar in operative position as shown in Fig. 1 is provided and in the form shown comprises parallel arms 9 and 10 formed of heavy wire or a small metal rod, said arms being connected at one end by a U-shaped loop 11, said loop being joined to said arms by two laterally extending parallel loops 12 and 13 which project in a plane at right angles to the loop 11 and are designed to form recess engaging fingers for insertion in the latch receiving recess 2 of the door jamb. The free ends of these arms 9 and 10 are bent to form substantially rectangular loops as 14 which are designed to encircle a nut 15 which is provided in its opposed edges with spaced notches 16, the notches in one edge registering with those in the opposite edge to receive the opposite ends of the loops 14 as is clearly shown in Figs. 1, 5 and 6. A screw 17 is operatively mounted in the nut 15 and is provided at one end with an operating handle 18 and which is designed for engaging one of the sockets 7 in the cross bar 6 and forcibly holding it in clamping engagement with the door jamb 1 and the door 3, the loops 12 and 13 of the connector 8 co-operating therewith in this 55 clamping action, as is shown clearly in Fig. 1. A U-shaped clevis or guide 19 is shown straddling the screw 17 and forming a guide therefor and has eyes 20 provided in its ends which are slidably engaged with the arms 9 and 10 of the connector 8.

In the use of this improved door securer, the loops 12 and 13 of the connector 8 are first inserted in the recess 2 of the door jamb 1 and the door is then closed with the connector projecting inwardly between said door and jamb and with the loops 12 and 13 engaging the inner wall of said recess. The cross bar 6 is then inserted between the arms 9 and 10 of said connector and positioned to span the joint between said door and jamb and when so positioned, the screw 17 is turned inwardly through the nut 15 with its inner end engaging one of the sockets 7 in said cross bar. This screw is tightened until said door and frame are reliably and firmly clamped between the loops 12 and 13 and the cross bar 6. The cross bar 6 is arranged in the position shown in Fig. 1 when the inner faces of the door and jamb are disposed flush with each other as shown, but when they are not flush, and the door is

spaced inwardly from the jamb as shown in Fig. 6, the position of the cross bar is reversed and the end of the short arm 5 thereof is engaged with the door while the inner end of the long arm is engaged with the jamb, the screw being tightened to bindingly connect said bar in operative position in the manner above described.

From the above description, it will be obvious that when this improved device is applied, access to the room is prevented until the securer is released and no unauthorized person can enter a room so equipped.

I claim as my invention:

- 15 1. A door securer comprising a cross bar, a connector for said bar comprising a pair of parallel arms connected at the end and straddling said bar, laterally extending loops disposed adjacent said connected ends, the free ends of said arms being bent to form nut receiving loops, a nut having notches therein for engaging said loops, a screw operatively mounted in said nut, and a guide
- 20

for said screw slidably mounted on said arms.

2. A door securer comprising a cross bar, a connector for said bar comprising a pair of parallel arms connected at one end and straddling said bar, laterally extending loops disposed adjacent said connected ends, the free ends of said arms being bent to form nut receiving loops, a nut having notches therein for engaging said loops, a screw operatively mounted in said nut, and a U-shaped guide spanning the space between said arms and having eyes at its free ends slidably engaged with said arms to form a guide for said screw.

In testimony whereof I have hereunto set my hand in presence of two subscribing witnesses.

JESSE W. SIMMONS.
